Patented Aug. 6, 1918.

UNITED STATES PATENT OFFICE.

HERMAN A. SCHMIDT, OF DETROIT, MICHIGAN.

MUFFLER.

1,274,943.

Specification of Letters Patent. Patented Aug. 6, 1918.

Application filed April 23, 1917, Serial No. 163,861. Renewed June 20, 1918. Serial No. 241,084.

To all whom it may concern:

Be it known that I, HERMAN A. SCHMIDT, a citizen of the United States of America, residing at Detroit, in the county of Wayne 5 and State of Michigan, have invented certain new and useful Improvements in Mufflers, of which the following is a specification, reference being had therein to the accompanying drawings.

10 This invention relates to mufflers especially designed for the exhaust or manifold of an internal combustion engine, although the device may be used for silencing the exhaust of steam or gases from conduits.

15 The primary object of my invention is to provide a muffler having a series of spaced baffling members which will retard and positively reduce to atmospheric pressure, gases passing therethrough, without over-

20 heating of the device or clogging thereof due to deposits from exhaust gases.

A further object of my invention is to provide a muffling device wherein the parts are constructed with a view of reducing the cost 25 of manufacture and at the same time retain those features by which durability, simplicity of construction and ease of assembling are secured.

Reference will now be had to the drawing, 30 wherein—

Figure 1 is a longitudinal sectional view of the muffler, and

Figs. 2 to 5 inclusive are views in elevation of detached baffle members.

35 In the drawing, 1 and 2 denote inner and outer cylindrical shells of the same length and material, the inner shell 1 being disposed in concentric spaced relation to the outer shell 2 to provide an annular air space 3, also clearance for a cover 4 on the inner shell 1, said cover being preferably made of asbestos, which together with the air space 3 will tend to deaden any sound within the muffler and at the same time prevent overheating of the outer shell.

40 Engaging the ends of the inner and outer shells 1 and 2 respectively, are caps 5 and 6 connected by a plurality of tie rods 7 having heads 8 at the cap 5 and detachable nuts 9 at the cap 6. The cap 6 has a concentric connection 10 for an inlet pipe 11, and the cap 5 has an offset outlet connection or exhaust 12, which is provided with a flattened or restricted portion 13.

45 Arranged on the tie rods 7 and main-

tained in spaced relation by long and short sleeves 14 are a series of baffle members designated 15, 16, 17, 18, 19, 20 and 21. The baffle member 21 is in proximity to the inlet pipe 11 and serves functionally as a deflector, said member being conical shaped so that gases entering the inner shell 1 will be deflected toward the walls thereof or the edges of said baffle member, which are in spaced relation to the inner shell 1.

50 The baffle members 20 and 15 are identical in construction and one of these members is shown in Fig. 2 in the form of a disk having parallel slots 22. The baffle members 20 and 15 engage the walls of the inner shell 1 and it is necessary for gases to pass through the slots 22. The baffle member 20 may be positioned relative to the baffle member 15 so that the slots 22 of the member 20 are at right angles to the slots of the baffle 55 member 15.

55 The baffle members 19 and 17 are identical in construction and one of these members is shown in Fig. 4 consisting of a plate substantially rectangular and having shell contacting edges 23 and other edges 24 coöperating with the inner shell in providing openings adjacent said shell, through which gases must pass.

60 The baffle members 16 and 18 are identical in construction and have been shown in Figs. 3 and 5 respectively. These baffle members are in the form of disks having a series of parallel slots 25 and when placing said baffle members in position, the baffle member 18 has the slots thereof at right angles to the slots of the baffle member 16.

65 The course of gases through the muffler has been indicated by arrows and it will be noted that the gases are sufficiently retarded so as to be reduced to atmospheric pressure before final exhaust, consequently all noise is eliminated or silenced by the device.

70 I attach considerable importance to the manner of assembling the various baffle members, as in some instances the number of members may be decreased while in other instances the number of members may be increased by using short or longer spacing sleeves on the tie rods. It is therefore possible to adapt the muffler to various kinds of exhausts, so that irrespective of the intensity or pressure of the exhaust it will be possible to silence the same. Furthermore, the manner of assembling the various parts 75

permits of the muffler being cleansed from time to time and the simple construction reduces the cost of manufacture to a minimum.

One embodiment of my invention has 5 been illustrated, but it is to be understood that the structural elements are susceptible to such variations and modifications as fall within the scope of the appended claim.

What I claim is:—

- 13 A muffling device comprising an outer cylindrical shell, an inner cylindrical shell in spaced relation to said outer shell, caps on the ends of said shells, gas inlet and exhaust connections for said caps, tie rods extending through said inner shell and connecting said cap, baffle members on said rods and in spaced relation, one of said baffle members being conical and pointed toward the gas inlet connections and having its edges 15 spaced from said inner shell, two of said baffle members having a pair of slots with said members positioned with the slots of one member parallel with the slots of the other

member and the edges of both of said members engaging said inner shell, two more of 25 said baffle members having each a plurality of slots with one of said members positioned with the slots thereof at right angles to the slots of the other member, and the edges of 30 said members in engagement with said inner shell, and the remaining two of said baffle members being imperforate and substantially rectangular with shell contacting edges, the arrangement of the baffle members 35 being such that the slots of four of said members coöperate with the edges of the imperforate members, the conical member and the inner shell in forming a tortuous passage for gas through the inner shell.

In testimony whereof I affix my signature 40 in the presence of two witnesses.

HERMAN A. SCHMIDT.
